Primary Examiner — Robert M Spear*Assistant Examiner* — Ryan Harvey(74) Attorney, Agent, or Firm — The Villhard Patent Group(57) CLAIM

What is claimed is the ornamental design for a football shaped boat bumper.

DESCRIPTION

FIG. 1 illustrates a perspective view of a football shaped boat bumper.

FIG. 2 illustrates a top view of a football shaped boat bumper; and,

FIG. 3 illustrates another perspective view of a football shaped boat bumper.

The broken lines illustrate portions of the article that form no part of the claimed design.
